SMOKING PIPE AND THE LIKE

Herman David Rudolph Mühlchen, Hoboken,
N. J.; John Gerhart Christian executor of Her-
man David Rudolph Mühlchen, deceased

Application July 26, 1939, Serial No. 286,571

2 Claims. (Cl. 131—215)

This invention relates to new and useful im-
provements in a smoking pipe and the like.

The invention has for an object the association
of a novel mechanism for supporting a piece of
absorbent material in the smoke passage of the
stem of a smoke pipe, or cigarette holder or
similar article.

The invention proposes to so support the ab-
sorbent material that it may easily be removed
and replaced when desired.

More specifically the invention proposes to
characterize the supporting means mentioned in
the previous paragraphs by a narrow stem of rigid
material extending longitudinally of the stem of
the smoking pipe or cigarette holder, and piv-
otally mounted at its rear end, and intermediate
of its ends provided with parallel flanges adapted
to resiliently clamp the absorbent material, in
extending into and opening in the side of the
pipe stem.

Still further the invention contemplates a
novel means for releasably holding the front end
of said narrow stem adjacent the pipe stem so
that the said narrow stem may be pivotally
opened when desired to give access to the ab-
sorbent material.

Still further the invention proposes the con-
struction of an article as mentioned which is
simple and durable and which may be manufac-
tured and sold at a reasonable cost.

For further comprehension of the invention,
and of the objects and advantages thereof, ref-
erence will be had to the following description
and accompanying drawing, and to the appended
claims in which the various novel features
of the invention are more particularly set forth.

In the accompanying drawing forming a ma-
terial part of this disclosure—

Fig. 1 is a side elevational view of a smoking
pipe constructed in accordance with this inven-
tion.

Fig. 2 is a fragmentary enlarged longitudinal
sectional view of a portion of Fig. 1.

Fig. 3 is a fragmentary enlarged horizontal
sectional view taken on the line 3—3 of Fig. 2.

Fig. 4 is a transverse vertical sectional view
taken on the line 4—4 of Fig. 2.

This invention relates particularly to a smok-
ing stem 10 of a smoking pipe or other similar
article. A ring 11 is fixedly mounted upon the
pipe stem 10. A narrow stem 12 of rigid material
extends longitudinally of the pipe stem and
at its rear end is pivotally mounted upon the
ring 11. The pivotal connection is formed by
the rear end of the narrow stem 12 being of bi-

furcated constructed so as to have spaced finger
portions 12a. These finger portions straddle
a lug 13 projecting from the ring 11. A pintle
pin 14 engages through the fingers 12a and the
lug 13 for accomplishing the pivotal connection
for these parts.

A pair of spaced parallel flanges 15 are mount-
ed upon the narrow stem 12 at the intermediate
position of its length and normally extends into
10 an opening 16 formed in the side of the pipe
stem 10. A piece of absorbent material 17 is
pressed in between the flanges 15 and is fric-
tionally held by these flanges. This piece of
15 absorbent material 17 is of a height slightly
greater than the height of the flanges 15 and so
extends into the smoke passage 10a of the pipe
stem 10.

A means is provided for releasably holding the
front end 12b of the narrow stem 12 adjacent
20 the pipe stem. This means includes a socket
member 18 mounted upon the pipe stem and co-
operative with a bolt element 19 mounted upon
the narrow stem 12. This bolt element is in the
form of a rivet having a hook shaped head. This
hook shaped head is adapted to engage into a
complimentary receiving opening formed in the
socket member 18. A small leaf spring 20 is
25 mounted upon and between the flanges 12a and
extends into an elongated opening 21 formed in
the lug 13. The pintle 14 also passes through the
opening 21. The leaf spring 20 has an offset cen-
30 tral portion engaging against one end of the
elongated opening so as to resiliently urge the
narrow stem 12 longitudinally in a direction so
that the hook end of the bolt element 19 engages
35 the opening 18a of the socket member.

The operation of the device is as follows:

With the parts in the position illustrated in
Fig. 2 the pipe or other similar article is ready
40 to be used. The tobacco juices or other fluids
which may enter the smoke passage of the pipe
stem 10 will be absorbed by the absorbent ma-
terial 17 when these fluids reach the area of the
absorbent material. When the material 17 be-
comes saturated and it is necessary to be re-
placed, the narrow stem 12 may be pivotally
opened as indicated by the dot and dash lines in
Fig. 1. To do this it is merely necessary to place
one's finger nail beneath the front end 12b of
45 the stem 12 and then to force the stem 12 slight-
ly forwards and at the same time pivoting the
stem 12 downwards so that the bolt element 19
disconnects from the socket member 18.

The stem 12 now swings open and the absorb-
ent material 17 is accessible. It may easily be

pulled out from between the flanges 15 and a new piece replaced. To close the stem 12 it is merely necessary to pivot it back into its original position and the bolt element 19 will snap into the opening 18a of the socket member. The leaf spring 20 will hold the parts in this position.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. In a smoking pipe, and the like, having a pipe stem for the passage of smoke which is formed with a side opening, a closure for said opening comprising a narrow stem of rigid material extending longitudinally of said pipe stem across and closing said side opening with its ends spaced substantial distances from said side opening, means for pivotally mounting the rear end of said narrow stem on the adjacent portion of said pipe stem, a socket member mounted on said pipe stem at a point adjacent the front end of said narrow stem, and a bolt element mounted upon the front end of said narrow stem and engaging said socket member for releasably holding said narrow stem, whereby one may engage the front end of said narrow stem to pivot same open and have a substantial mechanical advantage for overcoming sticking thereof, said bolt element and socket member having complementary hook portions engaging each other longitudinally of said stems, and said means for pivotally mounting the rear end of said narrow stem comprising lugs on said stems, a pintle pin mounted in an opening in one of said lugs and

engaging a slot in another of said lugs, and a leaf spring mounted in said latter opening on one of said lugs and engaging another of said lugs resiliently urging said narrow stem longitudinally of said pipe stem for maintaining the engagement of said hook portions.

2. In a smoking pipe, and the like, having a pipe stem for the passage of smoke which is formed with a side opening, a closure for said opening comprising a narrow stem of rigid material extending longitudinally of said pipe stem across and closing said side opening with its ends spaced substantial distances from said side opening, means for pivotally mounting the rear end of said narrow stem on the adjacent portion of said pipe stem, a socket member mounted on said pipe stem at a point adjacent the front end of said narrow stem, and a bolt element mounted upon the front end of said narrow stem and engaging said socket member for releasably holding said narrow stem, whereby one may engage the front end of said narrow stem to pivot same open and have a substantially mechanical advantage for overcoming sticking thereof, said bolt element and socket member having complementary hook portions engaging each other longitudinally of said stems, and said means for pivotally mounting the rear end of said narrow stem comprising lugs on said stems, a pintle pin mounted in an opening in one of said lugs and engaging a slot in another of said lugs, and a leaf spring mounted in said latter opening on one of said lugs and engaging another of said lugs resiliently urging said narrow stem longitudinally of said pipe stem for maintaining the engagement of said hook portions, and said leaf spring passing through said slot and resiliently engaging one end of said slot.

40 HERMAN DAVID RUDOLPH MÜHLICHEN.
